By Geo. Himmel Attorney

UNITED STATES PATENT OFFICE.

LEAH F. VAN ARNAM, OF GLOVERSVILLE, NEW YORK.

DESIGN FOR A DOLL.

Application filed May 24, 1922. Serial No. 2,405. Term of patent 14 years.

To all whom it may concern:

Be it known that I, LEAH F. VAN ARNAM, a citizen of the United States, residing at Gloversville, in the county of Fulton and State of New York, have invented a new, original, and ornamental Design for a Doll, of which the following is a specification, reference being had to the accompanying drawing, forming a part thereof.

The figure is a perspective view of a doll, showing my new design.

What I claim is:

The ornamental design for a doll, as shown.

LEAH F. VAN ARNAM.
